CLAIM

The ornamental design for a height adjustable portable camping chair, as shown and described.

DESCRIPTION

FIG. 1 is a front perspective view of a height adjustable portable camping chair in its first position, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the height adjustable portable camping chair in its second position; and,

FIG. 9 is a front perspective view of the height adjustable portable camping chair in its third position.
 The broken lines shown in the drawing are for the purpose of illustrating environmental structure and form no part of the claimed design.
